UNITED STATES PATENT OFFICE.

MATHEW HILGERT, OF NEW YORK, N. Y.

ORTHOPEDIC SHOE.

Application filed February 15, 1923. Serial No. 619,131.

This invention relates to boots and shoes, and more particularly to orthopedic shoes, that is, shoes which, by their features of construction, are designed to correct weakness and deformity of the lower limbs or feet from any cause. In my Patent No. 1,039,396, granted September 24, 1912, is disclosed a shoe construction by which I have been able to correct defects in locomotion due to an unbalanced muscular condition of the foot. 5

Objects of the present invention are not only to deal with and correct such abnormality but further to enable persons suffering from infirmities of the lower limb or 10 limbs such as weakness, joint disease, atrophy, or partial paralysis, such, for example, as may result from the disease known as infantile paralysis, to walk in a comfortable and natural manner. I have found that the 15 positions and movements of the hip and knee joints may be controlled by a shoe of special construction, so that persons unable to walk at all or only by the aid of crutches or other auxiliary support are enabled not only to 20 walk in a natural manner, but also to have the circulation and congested conditions of the limbs so improved that natural cure of the infirmity is greatly accelerated. This 25 result is brought about by restoring to normal balance the entire muscular organization of the foot and then so supporting the foot and controlling the tibia and fibula above the ankle and through them the femur that, when 30 the weight of the body begins to bear on the foot, the knee and hip joints will be controlled and thrown into their natural and proper positions to support the weight of the 35 body.

In developing the structure of the shoe by 40 which these results are obtained, I first consider the requirement of the individual whose locomotion is to be corrected and if, as is usually the case, the foot muscles are out of balance, I provide inside the shoe a filler 45 made preferably in accordance with my patent above mentioned to secure the proper balance of the foot muscles, and then incorporate in the shoe means for transmitting the foot pressure to the leg bones to cause 50 bending of the knee and hip joints in a natural manner. Such means may comprise either means for controlling the movement of the leg bones and joints laterally of the foot or means for controlling the movement 55 of the leg bones and joints longitudinally of the foot, or both, as individual require- 60 ments may dictate. For controlling the longitudinal movements I employ a counter and counter extension of special construction to be explained later in detail, and for controlling the lateral movements I provide a tongue and stiffener of special construction which will be fully explained.

For controlling the longitudinal movement of the leg bones and joints I provide, as 65 shown, a stiffener at the inner side of the foot which preferably is formed by an extension of a stiff counter of sole leather or other suitable material, and in cases where greater rigidity of the extension lengthwise of the 70 foot is required and to prevent bending or buckling of the counter extension in that direction, a resilient member of whalebone or steel is firmly secured to the counter extension on its outer side. The extension and 75 resilient member extend above the ankle joint and are secured to the leg of the shoe so that when the shoe is laced a firm connection between the foot and the principal leg bone or tibia is established through the extension, its stiffener and the counter, and by this connection the position of these bones longitudinally relatively to the foot is determined.

The special construction by which the control of the position of the leg bones laterally 80 of the foot is effected may as shown, comprise a tongue which is wide as compared with the usual shoe tongue, is shaped to the transverse and longitudinal curves of the 85 front surfaces of the tibia and instep, and is 90 stiffened against bending laterally of the foot. When such a tongue is clamped to the front 95 surfaces of the tibia and to the outer surfaces of the scaphoid, cuneiform, and other tarsal bones forming the instep, by the shoe lacing, the tongue, by reason of its inherent stiffness laterally of the foot, establishes a firm relation between the foot and tibia so that the 100 position of the tibia, and hence of the knee and hip joints, is controlled by the foot. Thus, if the knee tends to bend inwardly, the pressure of the balanced sole on the ground acts through the stiffened tongue to throw it outwardly, and conversely, if the knee tends to swing outwardly, it is thrown inwardly to its 105 normal position.

In certain hip joint diseases, where luxation occurs unless the patient contorts the limb and walks lame, I have been able, by providing a shoe made in accordance with this invention as above explained, to control the femur and maintain its head in the cup-

shaped cavity of the acetabulum, thus enabling the patient to walk in a natural manner.

In certain cases, especially where the conditions are such that the patient has a tendency to drag either or both toes when attempting to walk, a resilient member is provided between the inner and outer soles extending substantially to the toe. By properly shaping this member, and relating it to the counter extension, the foot may be held by the shoe in such a position that the toe will clear the ground without dragging. When the weight of the body is brought down on the foot the resilient member yields and allows the sole to assume its normal foot supporting position.

To render the shoe comfortable and easy to the foot, suitable padding such as soft felt is suitably located. Such padding may, in thickness and location, take into consideration the form and peculiarities of the individual foot and correct foot abnormalities such as low instep.

Shoes of this kind will find a wide use not only in relieving conditions due to weakness and deformity of the lower limbs but also in cases where, for any reason, unusual support and protection for the ankle are necessary or desirable.

Other objects of the invention are to provide a novel construction of tongue or stiffener, and a novel construction of combined counter and ankle brace.

These and other objects of the invention will appear more fully from the following detailed description when read in connection with the accompanying drawing and will be pointed out in the appended claims.

The novel construction of the shoe tongue herein shown and described but not claimed per se is being claimed in a divisional application Serial No. 235,198 filed November 23rd, 1927.

In the drawings,

Fig. 1 is a side view of my complete shoe, parts being broken away and in section;

Fig. 2 is a perspective detail of the counter and ankle stiffener;

Fig. 3 is a plan view, partly in section on the line 3—3 of Fig. 2, of the construction shown in Fig. 2;

Fig. 4 is a section on the line 4—4 of Fig. 1;

Fig. 5 is a view showing in perspective and transverse section the toe portion of the shoe; and

Fig. 6 is a perspective view of the bottom of the shoe with the heel and outsole removed.

The shoe may be, in general, of the usual welt shoe or other construction, the present invention being embodied in special construction which may be employed irrespectively of the type of shoe.

The counter of the shoe, including the ankle brace or stiffener, is shown separately in Fig.

2. The counter proper preferably is made in

two parts 2, 4 which are secured together by a back seam 6. The counter is preferably made of sole leather and hence substantial economy is effected by making it in two pieces, since smaller pieces of leather may be used. The counter is preferably molded to fit the ball of the heel. On the inner side of the shoe the counter is formed with an integral upward extension 8 which reaches nearly to the top of the leg portion of a high shoe. Outside of the upper portion of the extension 8 is a strip 10 preferably of tempered steel which is riveted at 12, 14 to the extension 8 with its widthwise dimension extending lengthwise of the shoe. At its lower end the steel piece 10 passes through a slit 16 in the counter to its inner side and has its lower end firmly secured to the counter 4, for example, by a rivet 18. The resilient strip 10 may yield to lateral flexure of the ankle joint but is substantially rigid against bending in a plane extending longitudinally of the foot. Outside of the steel piece 10 is a covering 20 of thin leather to protect the upper of the shoe, the covering being sewed by a seam 22 to the counter and counter extension 8. The counter and ankle stiffener, assembled as described, are incorporated into the shoe construction between the upper 24 and lining 26, the inner face of the counter and extension being, if desired, padded with felt to insure comfort to the wearer. After the counter has been built into the shoe the upper end of the extension is sewed to the upper and lining by a seam 28 to anchor the extension and stiffener securely to the leg of the shoe and render it effective to control bending of the leg of the patient longitudinally of the foot.

The novel construction of the tongue with which the shoe is provided is as follows: The tongue consists of an outer layer 30 of upper leather and an inner layer 32 of fabric such as canvas or the like. These layers extend beneath the vamp at the throat of the shoe and are secured to the upper by the vamp seam. The layers 30, 32 are preferably sewed together by a seam 34 about their peripheries to form a pocket or enclosure for the stiffening members located between them.

These members comprise a wide stiff piece 36 of material, for example sole leather skived to a thin edge at each side and at its lower end, and a tempered steel strip 38 arranged outside the leather piece 36 and secured to it by rivets 40, the widthwise dimension of the strip extending transversely of the shoe and substantially at right angles to the plane of the counter stiffener strip 10. The layers 30, 32 of the tongue and the piece 36 are wide as compared to the usual shoe tongue and are shaped to conform laterally to the front arch of the leg and instep, that is, to the shape of the front surfaces of the tibia, scaphoid, cuneiform and other tarsal bones, so as firmly to grip them when the shoe is

laced up. This construction renders the lateral stiffness of the resilient strip 38 effective to control the position of the bones of the leg by stiffening the ankle joint laterally 5 of the foot. On the inner side of the sole leather piece 36 is a thick pad of felt 42 the thickness of which may be varied to suit different foot requirements and to vary the apparent height of the instep. On the inner 10 side of the layer 30 is a thin pad of felt 44 to protect it from the steel piece 38 and rivets 40. In the construction described the tongue and counter stiffeners cooperate to afford adequate lateral and longitudinal control 15 of the bones of the leg through the ankle joint in a very effective manner.

In order to secure the desired control of the leg bones through the counter and tongue construction above described, it is important 20 that any unbalanced muscular condition of the foot be corrected and for this purpose I prefer to incorporate, in the present construction, a filler made in accordance with my patent above mentioned and by the method 25 disclosed in my Patent No. 1,032,672, granted July 16, 1912. The filler, as shown at 60 in Fig. 5, consists of a false inner-sole which is thickened on one side or the other, depending upon the muscular condition of 30 the foot for which it is intended, to support one side of the foot and relieve abnormal strain upon the ligaments of the foot. The upper or inner face of the filler 60 is preferably contoured to fit the bottom of the foot 35 and the lower or outer face is shaped to fit the inside tread of the shoe, and the thickness of the filler is varied transversely to overcome any tendency of the foot to "roll" transversely to one side or the other.

40 The filler 60 is applied to the last over which the shoe is made so that the normal appearance and size of the shoe are not affected and, when properly designed with reference to the particular conditions found in an individual foot, tends to restore to 45 normal balance the entire muscular organization of the foot. The shoe is provided, as shown, with the usual bottom filler 62 applied to the outer face of the innersole 53 and with an outersole 64 attached by a welt 58 in the usual manner.

By means of the filler 60 and the construction of the tongue and counter above described, I am able, by restoring the normal 55 balance of the foot and counteracting any tendency of the foot to roll, to control the action of the leg bones and the knee and hip joints so that persons afflicted with disease or malformation of these bones or joints, or 60 having weakness or paralysis of the leg muscles, are enabled to walk with ease in a substantially natural manner.

When the pressure of the foot and shoe in walking is brought to bear on a tread surface, 65 the proper balanced pressure of the foot is

effected by the filler and this pressure is then transmitted through the stiffened ankle joint to the leg bones, causing the leg at the knee and hip joints to bend in its proper and natural manner. Of course, when the balance of 70 the foot is normal and no correction is required, the filler may be made uniform in thickness or omitted, in which case the novel construction of the counter and tongue will act to transmit the foot pressure to the leg 75 bones and control their movement.

In some cases of defective locomotion, for instance where there is a tendency for the toe to drag upon the ground, it is desirable to control the position of the forepart of the 80 foot relatively to the rear part. For this purpose a sole stiffener is provided which controls the contour of the sole in a vertical plane and in the instance noted is bent upwardly at its forward end to lift the toe of 85 the shoe and prevent dragging of the toe as the leg is swung forward in taking a step. As shown in Fig. 6, a usual shank stiffener 50 has secured thereto, or formed integrally therewith, a resilient prolongation 52 which 90 extends substantially to the toe of the sole and is preferably secured to the innersole 53 by a thread 54 extending repeatedly across the prolongation 52 and into the substance of the innersole at 56 on each side of the 95 prolongation 52. Preferably the extreme forward end of the prolongation is inserted at 58 in a slit formed in the substance of the innersole to help secure the prolongation to the innersole and insure its control of the 100 vertical flexure of the sole. By giving the proper vertical contour to the prolongation 52 the vertical position of the toe portion of the shoe and foot may be controlled when no weight is borne upon the foot. Thus, by giving 105 the resilient prolongation an initial set which will normally raise the toe of the shoe and foot when pressure of the foot on the ground is relieved, the leg and foot may be swung forwardly and any tendency of the toe to drag on the ground prevented. The resilient prolongation will yield when the foot is pressed upon the ground to allow the foot and shoe to assume their normal body supporting position.

Having thus described my invention, what I claim as new and desire to secure by Letters Patent of the United States is:

1. In an orthopedic shoe, a sole portion thicker on one side than the other to control 110 the position of the foot about its longitudinal axis when pressed upon the ground, and a shoe upper stiffened against bending at the ankle longitudinally and transversely of the shoe whereby the position of the foot upon 115 the ground determines by pressure transmitted beyond the ankle joint the position of the leg bones and assists them to support the body in case muscular control is weak.

2. An orthopedic shoe having its sole por- 120

- tion thickened locally at one side of the foot to balance or correct abnormal or unequal pressure of the foot at opposite sides thereof, and an upper stiffener incorporated therein 5 to stiffen the ankle joint transversely of the foot and thus render the foot pressure effective beyond the ankle joint to control the leg bones and supplement defective muscular control thereof.
- 10 3. In an orthopedic shoe, means for directing the transverse roll of the foot, and means for stiffening the ankle joint transversely of the foot to cause said roll, due to pressure of the foot upon the tread surface, to be transmitted to the leg bones to effect flexing of the knee joint when muscular control is defective.
- 15 4. An orthopedic shoe having its sole portion thickened locally to balance or correct abnormal or unequal foot pressure, an upper and counter stiffener constructed and arranged to stiffen the ankle against bending longitudinally of the foot, and a tongue stiffener constructed and arranged to stiffen the ankle against transverse bending, said stiffeners 20 acting to dispose the leg bones in predetermined relation to the walking plane as a result of foot pressure thereon.
- 25 5. In an orthopedic shoe, means for throwing the foot pressure to one side of the foot, and a shoe tongue stiffened against transverse bending at the ankle to cause pressure of the foot upon the ground to be transmitted to the leg bones and to throw the knee joint away from the side on which the pressure is 30 greater.
- 35 6. In a high shoe, the combination of a counter having an upward extension stiffened against bending longitudinally of the foot, and a tongue stiffened against bending transversely of the foot, said tongue being shaped to the transverse curve of the ankle and instep and adapted to be held thereagainst by the upper closing means.
- 40 7. A shoe having a tongue stiffener and a counter stiffener each comprising a leather piece and a thin resilient member secured thereto, the resilient members being disposed with their widthwise dimensions in different planes to impart stiffness to the ankle joint laterally and longitudinally of the foot.
- 45 8. A shoe having, in combination, a stiffened tongue and a stiffened counter, the tongue stiffener comprising a piece of heavy leather and a strip of steel secured together and the counter stiffener comprising an integral upward extension on the counter and a steel stiffener secured to the extension and to the counter, the strips being disposed in different planes to afford support to the ankle joint laterally and longitudinally of the foot.
- 50 9. In a shoe, the combination of a counter having an upward extension upon the inner side of the foot to form an ankle stay, a metallic element secured to said extension and counter to afford stiffness against bending of the ankle longitudinally of the foot, a wide tongue fitting the transverse curve of the ankle and instep, and a flat metallic element secured to the tongue and disposed at right angles to the plane of the counter element to stiffen the tongue against lateral bending of the foot.
- 55 10. A shoe having a tongue stiffener and an ankle stiffener, each comprising a leather base and a thin resilient member secured thereto.
- 60 11. An orthopedic shoe having its sole portion thickened locally to balance and correct abnormal or unequal foot pressure, an upper and counter stiffener constructed and arranged to stiffen the ankle against bending longitudinally of the foot, and a resilient sole stiffener prolonged substantially to the toe and contoured to hold the toe portion of the shoe flexed upward to prevent dragging of the toe upon the ground.
- 65 12. In an orthopedic shoe, means for throwing the foot pressure to one side of the foot, a shoe tongue stiffened against transverse bending at the ankle, and a shank stiffener having a prolongation extending substantially to the toe of the shoe, said prolongation being resilient and normally bent upwardly to hold the toe of the shoe raised when the foot is off the ground and capable of bending to allow the shoe to resume its normal shape when pressed by the wearer on the ground.
- 70 13. In testimony whereof I have signed my name to this specification.

MATHEW HILGERT.
